UNITED STATES PATENT OFFICE

ERNEST PAUL LAURENT, OF REIMS, FRANCE

LIFE-SAVING METHOD AND APPARATUS FOR SUBMARINE CREWS

Application filed January 9, 1929, Serial No. 331,369, and in France February 2, 1928.

My invention relates to a safety chamber for submarines destined for serving as a life-saver for the crew thereof. The characteristic of the invention resides in using a part 5 of one of the existing water-ballast tanks, normally operating as an ordinary water-ballast tank, for lodging the crew therein after it has been emptied. The part of the water-ballast tank in question therefore constitutes 10 a movable reservoir which may be detached from the submarine, and by reason of Archimedes principle, rises immediately to the surface. The invention provides means destined to fix the said movable water-ballast tanks 15 upon the shell of the submarine, the means and devices for emptying such reservoirs and finally the means for detaching the same from the submarine in order to provide life-saving equipment for the crew.

20 The invention will be more readily understood by referring to the accompanying drawing forming part of this specification and in which—

Fig. 1 is a section taken cross-ways through 25 a submarine showing the position of the movable water-ballast tanks;

Fig. 2 is a partial side view thereof;

Fig. 3 is a partial plan view thereof;

Fig. 4 is a section through a two way valve 30 for emptying the water-ballast tanks;

Fig. 5 is a sectional detail of the device for securing the water-ballast tanks to the shell of the submarine; and

Fig. 6 is a section through the man-holes 35 of the water-ballast tanks and the submarine.

Referring to the drawing more in detail, the movable water-ballast tanks 1 and 2 are fixed on each side of the hull of the submarine in the most convenient position and in a way 40 to obtain absolute water-tightness. Their construction corresponds exactly to that of the water-ballast tanks 3 and 4 placed on the port and star-board sides. In the case of stranding of the submarine, and according 45 to the position thereof on the bottom of the sea, one or the other of the water-ballast tanks 1 and 2 may be emptied into the interior of the vessel by means of a double valve 5 illustrated in Fig. 4. Once the emptying operation is

50 provided with suitable bolts and thus establishes communication between the interior of the submarine and the movable water-ballast tank. The man-holes are subsequently closed and the reservoir unbolted from the hull 55 which accordingly rises to the surface in view of Archimedes principle.

The man-holes 6 illustrated on a larger scale in Fig. 6 are provided in the surface of the shell opposite the movable-water ballast tanks and are disposed in axial alignment with the man-holes of the submarine. Fluid tightness is assured by joints of rubber or analogous material.

For buoyancy reasons the water-ballast 60 tanks which are detachably shown at 1 and 2 must be made up in a symmetrical form and preferably in the form of a right quadrangular prism.

Each movable water-ballast tank is furnished with two valves 5 destined to be connected to the water exhaust line and the water inlet line in order to allow the water-ballast tanks to operate normally during normal operation of the submarine. Furthermore, four auxiliary valves are provided for obtaining rapid emptying in case of accident and are preferably connected to an air compressor or the like.

In Fig. 4 is shown the double valve 5 permitting the water-ballast tank to be emptied. The manipulating handle 7 of the valve is disposed in the interior of the water-ballast tank and is adapted to be removed from the tumbler of the valve to permit separation of the water-ballast tank from the hull.

The water-ballast tank is fixed to the hull C by means of fastening screws 9 as shown in Fig. 5. The said screws engage in a tapped part 10 of the hull C. It is merely necessary to unscrew the said screws when the members of the crew have reclosed the manholes 6 after having passed into the water-ballast tank.

The water-ballast tank may, if desired, be provided with life-saving devices which are well known in the art such as tubes of oxygen and the like. Likewise it is to be understood that the particular embodiment has merely been disclosed by way of example and

that many changes might be made in the detail of my apparatus and the disposition of the parts thereof as well as the manner of operating the same without departing from the spirit of my invention as comprehended within the scope of the appended claims, the particular novel feature of my invention residing in the fact that water-ballast tanks in sections are employed which are adapted to be emptied and serve as safety chambers for the submarine crew, such water-ballast tanks being detachable from the submarine in case of shipwreck for saving the crew.

Having described my invention what I claim as new and desire to secure by Letters Patent of the United States of America is:

1. A method of saving submarine crews in case of disaster, which consists in emptying one of the water-ballast tanks of said submarine into the hull of said submarine, evacuating the crew of said submarine into said empty water-ballast tank, closing said empty water-ballast tank and detaching said water ballast tank from said submarine whereby said water-ballast tank rises to the surface with said crew.

2. In a submarine having a plurality of sectional water ballast tanks, means for releasably securing certain of said water ballast-tanks to the hull of said submarine, man-holes communicating between said certain water-ballast tanks and the interior of said submarine, means for emptying said certain water-ballast tanks into the interior of said submarine and means for rendering the manholes in said certain water-ballast tanks fluid-tight.

3. In a submarine having a plurality of sectional water ballast tanks, bolts for releasably securing certain of said water-ballast tanks to the hull of said submarine, man-holes communicating between said certain water-ballast tanks and the interior of said submarine, means for emptying said certain water-ballast tanks into the interior of said submarine and means for rendering the manholes in said certain water-ballast tanks fluid-tight.

4. In a submarine having a plurality of sectional water ballast tanks, means for releasably securing certain of said water ballast-tanks to the hull of said submarine, man-holes communicating between said certain water-ballast tanks and the interior of said submarine, a two-way valve for emptying said certain water-ballast tanks into the interior of said submarine adapted to establish normal operation of said certain water-ballast tanks during normal operation of said submarine, and means for rendering the manholes in said certain water-ballast tanks fluid-tight.

5. In a submarine having a plurality of sectional water ballast tanks, means for releasably securing certain of said water ballast-tanks to the hull of said submarine, man-

holes communicating between said certain water-ballast tanks and the interior of said submarine, means for emptying said certain water-ballast tanks into the interior of said submarine and detachable plates for rendering the manholes in said certain water-ballast tanks fluid-tight.

6. In a submarine having a plurality of sectional water-ballast tanks, bolts for releasably securing certain of said water-ballast tanks to the hull of said submarine, man-holes communicating between said certain water-ballast tanks and the interior of said submarine, a two-way valve for emptying said certain water-ballast tanks into the interior of said submarine adapted to establish normal operation of said certain water-ballast tanks during normal operation of said submarine, and means for rendering the manholes in said certain water-ballast tanks fluid-tight.

7. In a submarine having a plurality of sectional water ballast tanks, bolts for releasably securing certain of said water-ballast tanks to the hull of said submarine, man-holes communicating between said certain water-ballast tanks and the interior of said submarine, means for emptying said certain water-ballast tanks into the interior of said submarine, and detachable plates for rendering the manholes in said certain water-ballast tanks fluid-tight.

8. In a submarine having a plurality of sectional water-ballast tanks, means for releasably securing certain of said water ballast-tanks to the hull of said submarine, man-holes communicating between said certain water-ballast tanks and the interior of said submarine, a two-way valve for emptying said certain water-ballast tanks into the interior of said submarine adapted to establish normal operation of said certain water-ballast tanks during normal operation of said submarine, and detachable plates for rendering the manholes in said certain water-ballast tanks fluid-tight.

9. In a submarine having a plurality of sectional water-ballast tanks, bolts for releasably securing certain of said water-ballast tanks to the hull of said submarine, man-holes communicating between said certain water-ballast tanks and the interior of said submarine, a two-way valve for emptying said certain water-ballast tanks into the interior of said submarine adapted to establish normal operation of said certain water-ballast tanks during normal operation of said submarine, and detachable plates for rendering the manholes in said certain water-ballast tanks fluid-tight.

10. In a submarine having a plurality of sectional water-ballast tanks, a plurality of water-ballast tanks having the form of a right quadrangular prism cooperating with said first mentioned tanks, means for releasably
